UNITED STATES PATENT OFFICE.

WILLIAM H. AVERILL, OF BOSTON, MASSACHUSETTS, ASSIGNOR TO BELL CLIP MANUFACTURING CO., OF BOSTON, MASSACHUSETTS, A CORPORATION OF MASSACHUSETTS.

DISPLAY HOLDER FOR PRICE CARDS, ETC.

Application filed June 10, 1922. Serial No. 567,326.

To all whom it may concern:

Be it known that I, WILLIAM H. AVERILL, a citizen of the United States, residing at Boston, in the county of Suffolk and State of Massachusetts, have invented new and useful Improvements in Display Holders for Price Cards, Etc., of which the following is a specification.

The object of this invention is to provide a simple and inexpensive holder of attractive appearance, adapted to display conspicuously a card or slip bearing the price of an article of merchandise, or other indicia, the form and construction of the holder 15 being such that it may rest loosely on a horizontal support, such as the top of a show case, or may be associated with a carton containing the goods.

The invention is embodied as hereinafter 20 described and claimed.

Of the accompanying drawing forming a part of this specification,—

Figure 1 is a perspective view of a holder embodying the invention.

Figure 2 is an edge view of the same.

Figure 3 is a perspective view, showing an extension applied to the base of the holder, and a card displayed by the holder.

Figure 4 is an enlarged section on line 4—4 30 of Figure 3.

The same reference characters indicate the same parts in all of the figures.

A holder constructed in accordance with my invention includes a flat base formed to 35 have an extended and stable bearing on a flat support, such as the top of a show case, or the top of a box or carton 12, shown by dotted lines in Figure 1. The base is thin, so that it may be interposed between the top 40 of a lower carton 12, and the bottom of an upper carton 13 (Figure 2), the holder being thus supported with its jaws hereinafter described upstanding at one end of the upper carton, so that a card 14 engaged with the 45 holder may be displayed in close proximity to the carton.

The holder is provided with resilient card-grasping jaws, which are perpendicular to the base and located at one end thereof. 50 Said jaws are adapted to be flexed in opposite directions by a card inserted between

them, to grasp the card and hold it perpendicular to the base.

The holder is preferably constructed by bending a single length or blank of wire of 55 suitable gage, to form two outer portions 15, two intermediate portions 16, spaced from the outer portions, necks 17, 17, connecting the portions 15 and 16, a flexible arched outer jaw 18, upstanding from the outer portions 60 15, and formed from the central portion of the blank, and a pair of loops 19, upstanding from the intermediate portions 16, and formed from the end portions of the blank, said loops collectively constituting an inner 65 jaw.

The portions 15 and 16, and the necks 17, are all in the same plane, and collectively constitute a skeleton base, the thickness of which is determined by the gage of the wire. 70 The jaws are normally in the same plane, which is perpendicular to the plane of the base. The jaws are adapted to be flexed or displaced in opposite directions by a card 14, inserted between them, the jaws being thus 75 caused to grasp the card, as indicated by Figures 3 and 4.

The base constructed as described, is adapted to be inserted between two cartons, as indicated by Figure 2, and thus firmly 80 secured in position to operatively support the jaws and a card 14.

If desired, the holder may be used independently, the base resting loosely on a flat surface, and the jaws being perpendicular to 85 said surface. To increase the weight and area of the base, it may be provided with a separable extension, shown by Figures 3 and 4, and composed of a strip of resilient sheet metal, bent to form a neck 22, and arms 23, 90 adapted to normally spring together. The base is forced between the arms 23 and springs them apart, so that they are caused to firmly grasp the base.

I claim:

A holder of the character stated, composed of a length of wire, bent to form outer and intermediate portions, and necks connecting said portions, said portions and necks being arranged in the same plane, and 100 constituting a flat skeleton base, the thickness of which is determined by the gage of

the wire, a flexible arched outer jaw, formed from the central portion of the wire and upstanding from the outer base portions, and loops formed from the ends of the wire, and 5 upstanding from the intermediate base portions, said loops collectively constituting an inner jaw, and being normally in the same plane with the outer jaw, the base being

formed to have an extended bearing on a flat support, and the jaws being adapted to be 10 flexed in opposite directions by a card inserted between them to grasp the card and hold it at an angle with the base.

In testimony whereof I have affixed my signature.

WILLIAM H. AVERILL.
